UNITED STATES PATENT OFFICE.

WILLIAM F. TAYLOR, JR., OF PROVIDENCE, RHODE ISLAND, ASSIGNOR OF
ONE-HALF TO THOMAS D. TAYLOR, OF BOSTON, MASSACHUSETTS.

SWITCH.

SPECIFICATION forming part of Letters Patent No. 748,811, dated January 5, 1904.

Application filed March 30, 1903. Serial No. 150,143. (No model.)

To all whom it may concern:

Be it known that I, WILLIAM F. TAYLOR, Jr., a citizen of the United States, residing at Providence, in the county of Providence and 5 State of Rhode Island, have invented certain new and useful Improvements in Switches, of which the following is a specification.

This invention relates to certain new and useful improvements in railway-switches operated by electricity; and it has for its primary object to provide an improved switch of this class which may be easily controlled by the motorman or operator of the car by simply operating the mechanism which makes 10 or breaks electrical circuits through certain switch-controlling agencies arranged in the road-bed. The current for actuating the switch-controlling agencies is preferably obtained from the overhead wire. 15 The invention further has for its object to provide a novel means whereby the mechanism carried by the car for engaging the aforementioned agencies located in the road-bed are elevated or lowered, as the case may be. 20 Further objects and advantages will be fully set forth in the following description and claims.

In the accompanying drawings, in which similar parts are referred to by corresponding 30 designating characters, Figure 1 is a view in side elevation of the forward end of a car provided with my improvement and showing the coöperating parts carried by the car and road-bed, respectively, contacting with one another. 35 Fig. 2 is a view in end elevation. Fig. 3 is a top plan view of a portion of the car-frame, the body portion of the car being removed. Fig. 4 is a detailed view of one of the contact members carried by the car and the contact plates 40 or rails arranged in the road-bed. Fig. 5 is an end elevation thereof and partly in section; and Fig. 6 is a plan view of a portion of the road-bed, the switch-tongue, and the mechanism for operating the same; and Fig. 45 7 is a transverse section through the switch-mechanism casing.

1 indicates the main rails, 2 the rails of the siding, and 3 the switch-tongue pivoted at the juncture of the main and siding rails, as 50 at 4, so as to be capable of lateral movement in the customary manner.

The switch-tongue is controlled by suitable agencies which are arranged on each side of the switch-tongue, as will be apparent in view of the following description: Pivoted 55 to a bar α , downwardly projecting from the switch-tongue at a point adjacent its point, is one arm of a lever 5. This lever is approximately T-shaped, the lateral arm of which is suitably secured to the first-named 60 arm at a point adjacent its outer end and is journaled in the road-bed so as to be capable of an oscillatory movement. The outer ends of this T-shaped lever are provided with rollers 6 and 7, the function of which will be 65 hereinafter explained.

Arranged at each side of the switch-tongue and at a point below the same are motors 8, to the shafts of which are keyed pinions 9. These pinions mesh with intermediate pinions 10, which are journaled in suitable bearings 11 and which in turn mesh with the gear-wheels 12. The gear-wheels 12 are keyed upon the shafts 13, which shafts are also provided with star-wheels 14. It will therefore 75 be obvious that as the motors are energized movement will be imparted to the respective train of gears, which in turn will impart movement to the star-wheels 14. These rollers 6 are adapted to alternately engage 80 the respective star-wheels 14, and in Fig. 6 I have shown one of the rollers contacting with its star-wheel. As these star-wheels are rotated they impart an outward movement through the medium of the rollers 6 to the T- 85 shaped lever 5, and thereby swinging it upon its pivotal point, so as to move the switch-tongue laterally, when one roller 6 is acted upon and forced into engagement with its wheel, thereby providing means whereby the 90 switch-point can be alternately swung laterally in both directions.

Having thus described the means employed for operating the switch which is arranged in the road-bed, I will proceed to describe the 95 mechanism carried by the car which coacts therewith.

Mounted upon the car at points adjacent its forward and rearward ends are the swing-ing arms 15. These arms are provided with 100 bifurcated lower ends in which are journaled the contact shoes or disks 16. These

disks are insulated apart, the insulating composition being indicated by the reference-numeral 17. These arms 15 have their upper ends provided with shoulders 18, which abut

5 against the shoulders 19, carried by the brackets in which the arms are pivoted, whereby the downward movement of the said arms is limited. 20 indicates springs for holding the shoes in engagement with the contact-plates 10 arranged in the road-bed. These contact-plates, which are designated by the reference-numeral 21, are arranged in pairs and insulated apart, as at 22, and are arranged in the road-bed a short distance in front of each 15 switch-tongue throughout the entire length of tracks, so that as the car proceeds on its journey the numerous switches encountered can be readily operated. As heretofore stated, the power or electrical energy which 20 is employed for operating by my switch-operating means is obtained from the overhead trolley-wire through the medium of the trolley-pole, (not shown,) which is obtained in the following manner: 23 indicates a feed-wire which leads from the controller 24 to the inner end of the circuit make and breaker 25. 26 indicates contact-plates which are adapted to be engaged by the means 25 for completing the circuits through the wires 27 25 and 28, which lead from the said contact-plates through the pivoted arms 15 to the disks 16. 29 and 30 indicate wires which lead from the contact-plates 21 of the road-bed to the respective motors 8.

35 The circuits are formed as follows: As the circuit make and breaker 25 is swung so as to engage one of the contact-plates 26 the current passes from the controller through the wire 23 and thence through one of the wires 40 27 and 28 to one of the disks 16, which as it contacts with the plates 21 of the road-bed causes the current to pass through one of the wires 29 to one of the motors and thence to the rails through wires 38 and 39. The motor 45 when energized rotates and actuates the switch-lever, as heretofore described. To move the switch-point in an opposite direction, the circuit make and breaker is moved into engagement with the other contact-plate 50 26, which will form or complete the circuit with the other motor in a manner similar to the one previously described.

By reference to Figs. 3 and 4 of the drawings it will be observed that I have provided 55 novel means whereby the arms 15 can be readily elevated, the same comprising cords 33, one of which is attached to each arm, the said cords passing over suitable pulleys 34 and 35, respectively, and thence to the shafts 36, 60 upon which the same are wound by operating the handles 37, arranged upon the upper ends of the said shafts. In connection with my improvement I have found that by providing a casing, such as indicated by the reference-numeral 40, the motors and adjacent mechanism 65 for operating the switch-tongue are

greatly protected and that, further, by providing the rollers 6 and 7, the same engaging the bottom of the casing, the switch-lever 5 is more easily operated.

70

Having thus fully described my invention, I claim—

1. The combination with the switch-tongue and the contact-plates arranged in the road-bed, of means interposed between the said switch-tongue and plates for operating the said switch-tongue, alternately-actuated means for actuating said first-mentioned means and means carried by the car adapted to contact with the said plates whereby the 80 first-named means is actuated.

75

2. The combination with the switch-tongue of a motor arranged adjacent to the switch-tongue, means alternately actuated by the said motor pivotally connected with the 85 switch-tongue for moving the said switch-tongue and means for operating the said motor.

80

3. The combination with the switch-tongue of an electrical means arranged adjacent the 90 switch-tongue, contact-plates arranged in the road-bed, an approximately T-shaped lever operatively connected with the switch-tongue, means carried by the car adapted to contact with the said contact-plates and means 95 whereby the said first-named means is energized, when the means carried by the car and the said contact-plates are in engagement with each other.

90

4. The combination with the switch-tongue, 100 of a motor arranged at each side of the switch-tongue, a pivotally-mounted lever of approximately T shape operatively connected with the switch-tongue, means actuated by the said motors for alternately moving the said lever 105 and moving the said switch-tongue and means for actuating the said motors.

100

5. The combination with the switch-tongue of an approximately T-shaped lever, pivotally mounted and having one of its arms pivoted to the said switch-tongue, an electrical means arranged on each side of the switch-tongue, means for actuating the said means alternately, and means whereby, as the said last-named means are energized, the said 115 lever will be alternately actuated thereby.

110

6. The combination with the switch-tongue and the means arranged adjacent thereto, of contact-plates arranged in the road-bed, and electrically connected to the said means, a 120 pivoted arm carried by the car, contact-disks journaled in the said arm and insulated from each other, said disks being adapted to contact with said contact-plates, a circuit make and breaker carried by the car and electrical 125 connections between the said circuit make and breaker and the said disks.

120

7. The combination with the switch-point and the switch-throwing mechanism, arranged in the road-bed, of a pivoted arm carried by 130 the car for actuating the said mechanism, disks journaled in the lower end of the said

130

arm, a circuit make and breaker, electrical connections between the said disks and circuit make and breaker as a source of supply.

8. The combination with the car and a circuit make and breaker carried by the car, of a pivoted arm, a pair of disks journaled in the lower end of the said arm and being insulated apart, electrical connections extending through the said arm and connecting the said disks, a circuit make and breaker, the switch-tongue and means arranged in the road-bed, coacting with the means carried by the car, for actuating the said switch-tongue.

9. The combination with the switch-tongue of a motor arranged in the road-bed at a point below the switch-tongue, a contact-plate arranged in the road-bed, electrical connections between the said plate and the motor, means carried by the car adapted to contact with the said plates to complete the circuit whereby the said motor is operated, and means actuated by the said motor for operating the switch-tongue.

10. The combination with the switch-tongue, of a motor arranged on each side of the switch-tongue, a pivoted lever connected with the switch-tongue, means actuated by the said motors to swing the said lever, whereby it is alternately actuated by the respective motor, actuated means and means for operating the said means alternately.

11. In combination with the switch-tongue of an approximately T-shaped lever, pivotally mounted in the road-bed and having one of its arms pivoted to the switch-tongue, means arranged on the opposite sides of the said switch-tongue for alternately engaging the lateral arm of the said lever for moving the switch-tongue, and means for operating the said means.

12. The combination with the switch-tongue, of a motor arranged on each side of the switch-tongue, pinions carried on the shafts of the said motors, shafts arranged adjacent the motor-shafts and provided with pinions actuated by the first-named pinions, star-wheels carried by the last-named shafts, a means interposed between the said star-wheels and being pivotally connected with the switch-tongue, means whereby when the said motors are operated, the said means will be alternately moved into engagement with the respective star-wheels, and means for actuating the said motors.

13. The combination with the switch-point of an electrically-actuated means arranged on each side of the switch-tongue, an approximately T-shaped lever, pivoted beneath the switch-point and having one of its arms pivotally connected thereto, rollers journaled on the outer ends of the lateral arm of the said lever, means actuated by the said first-named means for engaging the said rollers to swing the said lever and means for actuating the first-named means.

14. The combination with the switch-tongue of a pivotally-mounted lever, said lever being pivotally connected with the switch-tongue, an electrically-actuated means arranged on each side of the said switch-tongue, and adapted to alternately swing the said lever, contact-plates arranged in the road-bed, electrical connections between the said contact-plates and the last-named means, and means carried by the car adapted to contact with the said plates, substantially as and for the purpose specified.

15. The combination with the switch-tongue of a motor arranged on each side of the switch-tongue, means actuated by the said motors for swinging the said switch-tongues, plates arranged in the road-bed adjacent to the said switch-tongue, said plates being insulated apart, electrical connections between the said plates and motors, and means carried by the car for engagement with the said plates.

16. The combination with the switch-tongue, a switch-operating mechanism arranged in the road-bed, and the contact-plates electrically connected therewith, of a means carried by the car for engagement with the said contact-plates, said means comprising a pivoted arm, disks journaled in the lower end of the said arm, a wire leading from each disk through the said arm, contact-plates carried by the car to which the said wires are secured, a circuit make and breaker adapted to engage the last-named contact-plates, a source of energy and means raising and lowering the said pivoted arm.

In testimony whereof I have affixed my signature in presence of two witnesses.

WILLIAM F. TAYLOR, JR.
